UNITED STATES PATENT OFFICE.

JACOB FELBEL, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

No. 920,850.

Specification of Letters Patent.

Patented May 4, 1909.

Application filed January 4, 1909. Serial No. 470,618.

To all whom it may concern:

Be it known that I, JACOB FELBEL, citizen of the United States, and resident of the borough of Manhattan, city of New York, 5 in the county of New York and State of New York, have invented certain new and useful Improvements in Type-Writing Machines, of which the following is a specification.

My invention relates to typewriting machines and more particularly to stop devices for arresting the platen at predetermined points in its rotation, the mechanism being devised more especially for use in billing and condensed record work.

15 The main object of the invention is to provide simple and efficient means of the character specified.

To the above and other ends which will hereinafter appear, my invention consists 20 in the features of construction, arrangements of parts and combinations of devices to be hereinafter more fully described and particularly pointed out in the appended claims.

25 In the accompanying drawings wherein like reference characters indicate corresponding parts in the various views, Figure 1 is an end elevation, partly in section, on an enlarged scale of part of a typewriting machine embodying my invention. Fig. 2 is an enlarged plan view of the same, the view including parts which are sectioned away in Fig. 1. Fig. 3 is an enlarged detail front elevation, partly in section. Fig. 4 is an enlarged detail perspective view of one of the clutch members. Fig. 5 is an enlarged detail perspective view of the other clutch member together with the rotative stop carrier which is formed as a part of said 30 clutch member. Fig. 6 is an enlarged detail fragmentary sectional view taken through the clutch members and the sprocket wheel connected therewith.

In the present instance I have shown my 45 invention embodied in the Monarch typewriting machine to which it may be readily applied without materially modifying the regular structure of said machine.

The top plate 1 supports standards 2 to 50 which fixed guide rails 3 are secured by screws 4. The rails 3 are oppositely grooved and contain anti-friction balls or rollers 5 which also run in opposite grooves 6 formed in a rear cross bar or traverse bar 7 constituting part of the paper carriage. Project-

ing forwardly from the rear bar 7 are side or end bars 8, these several bars forming in the main the platen frame or carriage. A cylindrical rotative platen 9 is secured to a platen shaft 10 by a set screw 11 which enters a threaded hole in the hub of the right-hand platen head 12 and bears against the platen shaft. The platen shaft extends through and is journaled in bearing openings in the end plates 8 and is provided at its ends with finger wheels 13 and 14 in the usual manner. The left-hand platen head is formed with line spacing ratchet teeth 15 with which a spring-pressed roller detent 16 co-operates. A line spacing pawl 17 is pivoted to and carried by an arm 18 and co-acts with the line spacing wheel under the control of a finger piece 19 to effect step-by-step line spacing movements of the platen. The right-hand end plate 8 of the carriage is 75 formed with an upwardly extending arm 20 provided with a finger piece 21 by which the carriage may be moved to the right and by which it may be controlled when released from its spring drum for rapid movement 80 toward the left. The parts thus far described are of the usual Monarch construction and further description thereof is deemed unnecessary.

To the right-hand end of the platen shaft 85 10, where it extends beyond the right-hand end plate 8 is secured a band or sprocket wheel 22. This sprocket wheel may be held to the shaft by a set screw 23 passing through a threaded opening in the hub of the wheel 22 90 and bearing against the platen shaft. The sprocket wheel 22 is thus operatively and rigidly connected with the platen to rotate therewith and constitutes a driving wheel as will hereinafter more clearly appear. A sec- 95 ond band or sprocket wheel 24 is provided to co-operate with the wheel 22. A long shouldered screw or bolt 25 is threaded into a tapped hole in the right-hand end plate 8 of the carriage, as indicated at 26. 100

27 is a clutch member comprising a sleeve 28 and a cup or housing 29, the sleeve and bottom of the cup being fitted to turn on the bolt 25. The sprocket wheel 24 is secured by a drive fit or otherwise upon said sleeve. 105 The cup portion of the clutch member is formed or provided with a series of teeth 30, preferably equal in number to the number of ratchet teeth 15 on the platen head. The teeth 30 radiate outwardly from the cup and 110

are adapted to coöperate with a single tooth 31 formed or provided interiorly of a second cup 32 forming part of a companion clutch member 33, likewise mounted to 5 rotate on the bolt 25. The clutch member 33 is provided with a sleeve 34. The clutch 27 is prevented from moving axially of the bolt by the hub of the sprocket wheel 24 and by a washer 36, interposed between the end 10 plate 8 and the sleeve 28 and hub of the sprocket wheel 24.

The clutch member 33 is formed or provided with a circular groove 37 to receive the rear forked end 38 of a clutch lever 39, which is pivotally supported at 40 upon a bracket 41 secured by screws 42 to the under side of the end bar 8. The fork 38 is provided at its ends with inwardly projecting studs 43 arranged on opposite sides of the 20 axis of the bolt and vertically one under the other. The clutch 33 is provided with a stop carrier 44, in the form of a circular disk, which as shown is formed integral with the clutch member, the said disk or carrier 44 in 25 the present instance constituting the outer wall of the groove 37 in which the fork of the clutch lever is arranged to operate.

The stop carrier 44 is perforated circularly near its perimeter with equi-distant holes 45, 30 preferably equal in number to the number of ratchet teeth on the platen head. A pin 46 on an arm 47 is adapted to enter any of the holes 45 according to adjustment of the arm, which is provided with a hub 48 which takes 35 a bearing on the barrel of the bolt 25. The arm 47 has a tension toward the perforated disk and hence a tendency to keep the pin 46 seated in the selected hole. The arm is provided with a finger piece 49 by which the arm 40 may be flexed or moved to disengage the pin from one hole and reengage it in another hole after a rotary movement of said arm.

The bolt is headed at 50 and at this portion is provided with a light spring 51 that presses 45 at one end against the head and at its opposite end against the hub 48 of the arm. This arm is formed with an extension or projection 52 that constitutes a stop, adapted to contact with one side of an arm 53 projecting outwardly from the end bar 8. Another 50 stop 54, preferably made integral with the perforated disk or carrier 44 is also adapted to contact with said arm 53, but on the opposite side thereof from that which the stop 52 55 contacts with. The two sprocket wheels 22 and 24 are connected together by an endless chain, band or belt 55.

The outer end of the clutch lever is fashioned into a handle or finger piece 56 and 60 said lever is held in either one or two positions by an arm 57 secured to the side bar 8 and having two notches or depressions 58, the outer end of which is engaged by the lever in the positions of the parts shown at Fig. 2. The said arm is preferably resilient,

so that the lever may snap from one notch to the other and be held or locked where set by the springiness and grip of the arm 57.

Referring more particularly to Figs. 1, 2, 3 and 6 the clutch members are in engagement 70 and the mechanism is in working condition. If now the platen be rotated the sprocket wheel 22, turning therewith, will drive the chain or band 55 and cause the wheel 24 to be driven, and since this wheel is fast on one 75 of the clutch members and the clutch members are in engagement the stop carrier 44 will be rotated simultaneously and carry with it the engaged stop 52. If the platen be rotated in the direction of the arrow *a* at 80 Fig. 1 the stop carrier will be caused to turn in the same direction as indicated by the arrow *b* and hence the stops 52 and 54 will travel therewith in the same direction or in the direction of the hands of a clock. In 85 rotating the platen in the direction of the arrow *a* the paper will be fed forwardly toward the printing point *x* but the platen will be arrested when the stop 52 arrives at the rear, lower side of the stop arm or bar 53. 90 In order to feed the paper farther in the same direction it is necessary to swing the handle end of the clutch lever 39 inwardly toward the platen. By this operation the rear forked end of the clutch lever will move the 95 clutch member 33 outwardly or toward the right. The rightward movement of the clutch member 33 forces the stop carrier arm 47 in the same direction, along the bolt, and against the tension of its spring 51, which is 100 provided more particularly to keep the arm in proper relationship to the perforated disk and yet permit the shifting movement of the clutch member 33 and its connected parts out of engagement with the clutch member 105 27. When the clutch member 33 has been moved to the right as just described the tooth 31 is moved out of engagement with the teeth 30 of the clutch member 27, thus 110 freeing the platen from the stopping devices and enabling it to be turned unlimited distances either forwardly or backwardly by means of the hand knobs or wheels 13 and 14 or by means of the line spacing mechanism. At this time however, the chain or band and 115 the band wheels, as well as the clutch member 27, all move when the platen is rotated, these devices being permanently connected with the platen.

In the working positions of the parts shown at Figs. 1, 2, 3 and 6 the platen may be arrested in its backward rotation by the engagement of the rotary stop 54 with the fixed stop 53. The adjustable stop 52 is shown set so as to allow the platen to be 120 rotated forwardly a distance of about 27 line spaces before arresting its movement. It will be understood of course that as the stop 52 travels around toward the stop 53 to 125 thus arrest the platen in its forward move- 130

ment, the stop 54 simultaneously travels around in the same direction and away from the fixed stop 53 and the distance which it thus travels will correspond to the distance 5 traveled by the stop 52 until it reaches the fixed stop 53. Hence, when the platen has been rotated backwardly sufficiently to bring the stop 54 back into contact with the stop 53, the stop 54 will have traveled backwardly the same distance that the stop 52 traveled forwardly. Thus the forward and backward rotations of the platen are equal in extent and it will be understood that this may be varied as may be necessary by adjustment of the stop 52. This adjustment is usually determined by the depth of the printed heading of the invoice or bill sheet when the mechanism is employed for condensed record work.

20 In view of my prior patent No. 902,572 dated November 3rd, 1908 it is not deemed necessary to describe in detail the operations of condensed billing with this mechanism.

While I have shown the perforated disk as 25 made integral with the clutch member 33, it may of course be made separate and connected with the clutch member. It will further be understood that the direction of movement of the sliding clutch member to 30 engage and disengage with its companion clutch member is wholly immaterial, that being dependent upon the character of the clutch lever employed. In this case I have shown a clutch lever of the first order and 35 hence when the handle end 56 is moved outwardly it causes an engagement of the clutch members and when it is moved inwardly causes a disengagement thereof. When the handle is held in the inner notch of the holding arm 57 the stop mechanism is in inoperative condition and of course at that time the platen may be rotated freely in either direction but when the handle of the clutch is seated in the outer notch the stop mechanism 40 is connected operatively with the platen and the platen is limited in its rotative movements both forwardly and backwardly by the stopping devices 52, 53 and 54 as before explained.

50 It will be noted from the foregoing that in the particular construction of mechanism herein shown and described one of the band wheels is connected to the platen shaft so as to be driven, so to speak, by the platen or at 55 the same time the platen is rotated by either of the hand wheels or by the line spacing mechanism; that the other of the band wheels is arranged at the rear of the carriage frame and connected to the first mentioned 60 band wheel by a flexible band which communicates the motion from the platen-driven band wheel to the said companion band wheel; that in this form of my invention the band wheels always rotate with the platen 65 though (as in another form of my invention,

the subject matter of pending application Serial No. 456,236) this is not essential when considering the invention from its broadest aspect; that there is a rotary stop carrier adapted to be coupled with and uncoupled from the band mechanism, comprising in this case the band and the two band wheels; that when the rotary stop carrier is connected with the band mechanism and therefore with the platen said carrier rotates but when disconnected from the band mechanism it remains at rest during the rotation of the platen; that therefore in its broader sense the essence of the invention may be said to consist in operatively coupling the rotary stop carrier with the platen through the band mechanism when it is desired to arrest the platen and in uncoupling the said carrier from the platen through the band mechanism when it is desired to have the platen 85 rotate indefinitely without hindrance; that this construction and mode of operation considered from the broad aspect are carried out both in the present form of my invention and in the form shown in my said pending application 456,236, in which application the invention is shown in an arrangement whereby the band wheels are adapted to be clutched to and unclutched from the platen instead of always running constantly with the platen 90 as in this case; that in the present arrangement of my invention the clutching mechanism is located at the rear of the platen frame and concentrically with the rear band wheel; that one member of said clutch mechanism 95 rotates always concurrently with said rear band wheel while the other member of said clutch mechanism is adapted to be maintained out of engagement with said constantly rotatable clutch member but is adapted 100 to be thrown into engagement therewith at any desired time so as to bring about a rotative action of the stop carrier which is connected to the shiftable clutch member; that the stop carrier in this instance carries a 110 permanently located stop and also an adjustable stop each adapted to coact with a relatively fixed stop on the framework of the carriage, but so far as the stops *per se* are concerned they may be otherwise arranged; 115 for example, there may be two stops on the framework and only one stop on the carrier and for further example there may be only two stops altogether, depending on whether or not it is desired to stop the rotation of the 120 platen both forwardly and backwardly; that if it be desired to rotate the platen in backward direction only then it will be necessary to use only the stops 54 and 53, while on the other hand if it be desired to stop the platen 125 only in its forward movement it will be necessary only to use the stops 52 and 53; that the said stops are separate from the traveling band in that they are not carried directly by the band but are carried by a 130

part adapted to be actuated by the band; that by the operation of a clutch the rotatory stop carrier is connected to be rotated by the chain which in turn is driven by the platen and that when said clutch is reversely operated the platen is left free to be rotated independently of said rotatory stop carrier.

Various changes may be made without departing from the spirit and scope of my invention.

What I claim as new and desire to secure by Letters Patent, is:—

1. The combination of a platen, a flexible band connected to be driven therewith, a rotatory stop connected to be driven by a movement of said band, and means for arresting said rotatory stop.

2. The combination of a platen, a flexible band, a rotatory stop to be driven by a movement of said band, a relatively fixed stop cooperative with the first mentioned stop to arrest the platen, and means for rendering said stops inoperative to arrest the platen.

3. The combination of a platen, a flexible band adapted to be driven when said platen is rotated, a rotatory stop carrier adapted to be driven by said flexible band, an adjustable stop mounted on said stop carrier, a relatively fixed coöperating stop, and means for coupling the stop carrier and adjustable stop to and for uncoupling them from the said flexible band.

4. The combination of a platen, a flexible band, a rotatory stop carrier, two stops carried thereby, one of which is adjustable, a relatively fixed stop on the framework of the machine, and clutch mechanism for coupling the stop carrier with the flexible band.

5. The combination of a platen, a platen shaft, a band wheel on the latter, a companion band wheel, a flexible band connecting said wheels, a rotatory stop carrier adapted to be coupled to and uncoupled from said band, the band, band wheels and stops determining the extent of rotation of said stop carrier.

6. In a typewriting machine, the combination of a rotative platen; a band which is movable concurrently with the platen; stops separate from said band but certain of which stops are moved by the band; and means for enabling the platen to rotate independently of said stops.

7. In a typewriting machine, the combination of a rotative platen; a band which is movable concurrently with the platen by a constantly maintained connection between the platen and band; stops separate from said band but certain of which stops are moved by the band; and means for enabling the platen to rotate independently of said stops.

8. In a typewriting machine, the combination of a rotative platen; a band which is movable concurrently with the platen; stops

separate from said band but certain of which stops are moved by the band; means for affording a relative adjustment between certain of said stops; and means for enabling the platen to rotate independently of said stops. 70

9. In a typewriting machine, the combination of a rotative platen; a platen frame; a band; a constantly maintained operative connection between said platen and band to cause the platen and band to move together; stops for arresting the platen, certain of said stops being held against movement on the platen frame, and certain of said stops being separate from but adapted to be moved by said band; means for affording a relative adjustment between certain of said stops; and means which enable the platen to turn independently of said stops. 75

10. In a typewriting machine, the combination of a rotative platen; a platen frame; a band; a constantly maintained operative connection between said platen and band to cause the platen and band to move together; stops for arresting the platen, one of said stops being fixed to the platen frame and two other of said stops being relatively adjustable and separate from but adapted to be moved by said band; and hand actuated means operable at will for operatively connecting said relatively adjustable stops with 95 and for disconnecting them from said band. 90

11. In a typewriting machine, the combination of a rotative platen; a band driven by the platen; stops for arresting the platen; certain of said stops being separate from but 100 rotative by said band; and means whereby the platen may be rotated independently of said rotative stop or stops.

12. In a typewriting machine, the combination of a rotative platen; a band driven by the platen; stops for arresting the platen, certain of said stops being separate from but rotative by said band; means for effecting a relative adjustment between certain of said stops; and means for rendering the stops inoperative to arrest the platen. 110

13. In a typewriting machine, the combination of a rotative platen, a band driven in unison with the platen, stops for arresting the platen, certain of said stops being separate from but rotative by said band; and hand actuated means operable at will for operatively connecting or disconnecting the rotative stop or stops and said band. 115

14. In a typewriting machine, the combination of a rotative platen; a band; stops for arresting the platen, certain of said stops being separate from but rotative by said band; constantly maintained operative connections between said band and platen; and means whereby the platen may be rotated independently of said rotative stop or stops. 120

15. In a typewriting machine, the combination of a rotative platen; a band; stops for arresting the platen, certain of said stops 125

being separate from but rotative by said band; means for effecting a relative adjustment between certain of said stops; constantly maintained operative connections 5 between said band and platen; and a hand actuated clutch operable at will for operatively connecting certain of said stops with said band.

16. In a typewriting machine, the combination of a rotative platen; a driving wheel turned concurrently with the platen; a driving wheel; a band for transmitting a rotative movement from the driving to the driven wheel; stops for arresting the platen, 15 certain of said stops being moved by the driven wheel; and means for rendering the stops inoperative to arrest the platen.

17. In a typewriting machine, the combination of a rotative platen; a driving wheel turned concurrently with the platen; a driven wheel; a band for transmitting a rotative movement from the driving to the driven wheel; stops for arresting the platen, 20 certain of said stops being moved by the driven wheel; and means for operatively connecting at will the movable stop or stops and said driven wheel.

18. In a typewriting machine, the combination of a rotative platen; a driving wheel turned concurrently with the platen; a driven wheel; a band for transmitting a rotative movement from the driving to the driven wheel; stops for arresting the platen, 30 certain of said stops being moved by the driven wheel; and a hand actuated clutch operable at will for effecting an operative connection between the movable stop or stops and said driven wheel.

19. In a typewriting machine, the combination of a rotative platen; a driving wheel turned concurrently with the platen; a driven wheel; a band for transmitting a rotative movement from the driving to the driven wheel; stops for arresting the platen; 45 a stop carrier for certain of said stops; and hand actuated means operable at will for effecting an operative connection between said stop carrier and the driven wheel.

20. In a typewriting machine, the combination of a rotative platen; a driving wheel turned concurrently with the platen; a driven wheel; a band for transmitting a rotative movement from the driving to the driven wheel; stops for arresting the platen; a rotative stop carrier for certain of said stops; and hand actuated means operable at will for effecting an operative connection between said rotative stop carrier and the driven wheel.

21. In a typewriting machine, the combination of a rotative platen; a driving wheel turned concurrently with the platen; a driven wheel; a band for transmitting a rotative movement from the driving to the driven wheel; stops for arresting the platen; a rotative stop carrier for certain of said stops; a companion clutch section on said carrier; a clutch section on the driven wheel; and hand actuated means operable at will for throwing said clutch sections into and out of coöperative engagement.

22. In a typewriting machine, the combination of a rotative platen; a driving sprocket wheel which is turned concurrently with the platen by a constantly maintained connection; a sprocket chain coöperating with 70 said sprocket wheel; stops for arresting the platen; a rotative stop carrier carrying certain of said stops, said stop carrier being rotated by said sprocket chain; and means for rendering said stops inoperative to arrest the platen.

23. In a typewriting machine, the combination of a rotative platen, a driving sprocket wheel which is turned concurrently with the platen by a constantly maintained connection; a sprocket chain coöperating with 85 said sprocket wheel; stops for arresting the platen; a rotative stop carrier carrying certain of said stops, said stop carrier being rotated by said sprocket chain; and hand actuated means operable at will for operatively connecting said stop carrier with the sprocket chain to be driven thereby.

24. In a typewriting machine, the combination of a rotative platen; a driving sprocket wheel which is turned concurrently with the platen by a constantly maintained connection; a driven sprocket wheel, a sprocket chain coöperating with said sprocket wheels; stops for arresting the 90 platen; a rotative stop carrier for certain of said stops; and means for rendering said stops inoperative to arrest the platen.

25. In a typewriting machine, the combination of a rotative platen; a platen shaft; a 105 platen frame; a fixed stop on the platen frame; a rotative stop carrier; two relatively adjustable stops carried by said stop carrier and coöperative with said first mentioned stop to arrest the platen; a wheel on the platen shaft; a band driven by said wheel and coöperative operatively with said rotative carrier to turn it; and means whereby said stops are rendered inoperative 110 to arrest the platen.

26. In a typewriting machine, the combination of a rotative platen; a platen frame; stops for arresting the platen; a driving sprocket wheel concentric with the platen and fixed to rotate therewith; a second 115 driven sprocket wheel; an endless sprocket chain coöperative with said sprocket wheels; a rotative stop carrier, certain of said stops being carried by said carrier; means for effecting a relative adjustment between certain of said stops; and hand actuated means operable at will for causing said stop carrier and said driven sprocket wheel to be rotated.

together or for enabling the driven sprocket wheel to travel independently of said carrier.

27. In a typewriting machine, the combination of a rotative platen; stops for arresting said platen, certain of said stops having a rotative movement; an endless band for causing the rotative stop or stops to rotate with the platen; and means operable at will for rendering said stops inoperative to arrest 10 the platen.

28. In a typewriting machine, the combination of a rotative platen; a platen shaft; a platen frame; a sprocket wheel rigidly mounted on the platen shaft; a second 15 sprocket wheel mounted on the platen frame; an endless sprocket chain coöperative with said sprocket wheels; a rotative stop carrier mounted concentrically with said second sprocket wheel; a clutch for connecting or 20 disconnecting at will said second sprocket wheel and said rotative carrier; and stops for arresting the rotation of the platen, certain of said stops being relatively adjustable, certain of them being rotative, certain of them 25 being carried by the platen frame, and certain of them being carried by said rotative carrier.

29. In a typewriting machine, the combination of a rotative platen; a platen shaft; a 30 platen frame; a sprocket wheel rigidly mounted on the platen shaft; a second sprocket wheel mounted on the platen frame; an endless sprocket chain coöperative with 35 said sprocket wheels; a rotative stop carrier mounted concentrically with said second sprocket wheel; a hand actuated clutch operable at will for connecting or disconnecting said second sprocket wheel and said rotative carrier; means for retaining the clutch 40 in either its engaged or released position; and stops for arresting the rotation of the platen, certain of said stops being relatively adjustable, certain of them being rotative, certain of them being carried by the platen

frame, and certain of them being carried by 45 said rotative carrier.

30. In a typewriting machine, the combination of a rotative platen; a platen shaft; a platen frame; a sprocket wheel rigidly mounted on the platen shaft; a second 50 sprocket wheel mounted on the platen frame; an endless sprocket chain coöperative with said sprocket wheels; a rotative stop carrier mounted concentrically with said second sprocket wheel; a clutch for connecting or 55 disconnecting at will said second sprocket wheel and said rotative carrier; and stops for arresting the rotation of the platen, two of said stops being relatively adjustable and carried by said rotative stop carrier and a 60 third of said stops being fixed to the platen frame.

31. In a typewriting machine, the combination of a rotative platen; a platen shaft; a platen frame; a sprocket wheel rigidly 65 mounted on the platen shaft; a second sprocket wheel mounted on the platen frame; an endless sprocket chain coöperative with said sprocket wheels; a rotative stop carrier mounted concentrically with said second 70 sprocket wheel; a clutch for connecting or disconnecting at will said second sprocket wheel and said rotative carrier; a stop fixed to the platen frame; a second stop fixed to the rotative carrier, a third stop mounted 75 concentrically with the rotative carrier and rotatively adjustable relatively thereto; and means for securing said third stop in its adjusted position on said carrier.

Signed at the borough of Manhattan, city 80 of New York, in the county of New York, and State of New York, this 2nd day of January, A. D. 1909.

JACOB FELBEL.
